UNITED STATES PATENT OFFICE

154,550

DESIGN FOR A CANOPY

Samuel B. Korman and Meyer Harrison, Pittsburgh, Pa., assignors to Kool Vent Metal Awning Corporation of America, a corporation of Pennsylvania

Application September 5, 1947, Serial No. 141,225

Term of patent 14 years

(Cl. D21—6)

To all whom it may concern:

Be it known that we, Samuel B. Korman and Meyer Harrison, both citizens of the United States, residing at Pittsburgh, in the county of Allegheny and State of Pennsylvania, have invented a new, original, and ornamental Design for Canopy, of which the following is a specification, reference being had to the accompanying drawing, forming part thereof.

Figure 1 is a front elevational view of a canopy embodying our new design, and

Figure 2 is a perspective view thereof looking at one side of the awning.

We claim:

The ornamental design for a canopy, as shown.
SAMUEL B. KORMAN.
MEYER HARRISON.
